UNITED STATES PATENT OFFICE.

DANIEL W. SNOW, OF FILLMORE, CALIFORNIA.

WIRE-ROPE SOCKET.

1,408,144.

Specification of Letters Patent. Patented Feb. 28, 1922.

Application filed June 27, 1921. Serial No. 480,639.

To all whom it may concern:

Be it known that I, DANIEL WILLIAM SNOW, a citizen of the United States, residing at Fillmore, in the county of Ventura and State of California, have invented 5 new and useful Improvements in Wire-Rope Sockets, of which the following is a specification.

My invention relates to a wire rope socket, 10 the principal objects of my invention being to provide a relatively simple and efficient socket connection between a wire rope or cable and a drill shank, further to provide a wire rope socket that may be readily assembled or taken apart and which when 15 properly connected will provide a firm and substantial connection between the wire rope or cable and the drill shank, and further to generally improve upon and simplify the 20 construction of similar types of existing sockets and connecting devices.

With the foregoing and other objects in view, my invention consists in certain novel features of construction and arrangement of 25 parts that will be hereinafter more fully described and claimed and illustrated in the accompanying drawings, in which:

Figure 1 is a vertical section taken centrally through a wire rope socket and connecting device of my improved construction.

Fig. 2 is a horizontal section taken on the line 2--2 of Fig. 1.

Fig. 3 is a horizontal section taken on the line 3--3 of Fig. 1.

Fig. 4 is an elevational view of one of the slips or wedge plates that is utilized in my improved socket connection.

Referring by numerals to the accompanying drawings which illustrate a practical embodiment of my invention, 10 designates the upper portion of a drill shank, and projecting upwardly therefrom is an axially disposed externally threaded stud 11 that is adapted to be engaged by the internally 15 lower threaded end of a tubular member 12 that forms the lower portion of the body of my improved socket connection.

The bore of chamber 13 that is formed through member 12 gradually decreases in 20 diameter toward its upper end, and the upper portion of said member 12 is provided with a relatively short internally threaded portion 14 that is adapted to receive the externally threaded depending 25 portion 15 of the upper member 16 of the socket connection. The bore or chamber 17

that is formed in this upper member 16 gradually tapers toward its upper end, and the size of said bore or chamber is such that it forms practically a continuation of the 60 tapered bore or chamber 13 in the lower socket member 12.

Members 12 and 16 are provided in their outer faces with recesses 18 that are adapted to receive spanner wrenches or the like, and 65 which are utilized in connecting or disconnecting the parts of the socket. The lower portion of the wire rope or cable 19 to which my improved socket is applied passes through an opening 20 in the upper end of 70 member 16 and downwardly through the tapered chamber within socket members 12 and 16, and the end portion of said rope or cable is untwisted for a short distance, and the core of said rope or cable within 75 the untwisted portion and within that portion immediately adjacent to the upper end of the untwisted portion is removed so as to receive the body portion of a spreader plug 20, and which latter is provided at its 80 upper end with an upwardly projecting pin 21 which enters the chamber formed in the lower end of the twisted end of the cable by the removal of the goods thereof.

The lower portion of the body or plug 85 20 tapers toward its upper end, while the upper portion of said body gradually tapers toward its upper end, and the untwisted wires of the cable are arranged so that they 90 extend downwardly over the inclined surfaces of the upper and lower portions of said plug.

Encircling the lower portions of the wires or those portions that are positioned on the 95 downwardly tapered lower portion of plug 20, is a ring 22 that occupies the lower portion of the chamber 13, and encircling the upwardly tapered upper portion of said plug and the portions of the wires that are disposed thereupon is a ring 23. Obviously, the 100 openings through rings 22 and 23 are tapered to correspond with the tapered surfaces of the plug 20, and when the parts are properly assembled, the rings 22 and 23 very effectively secure the untwisted end portions 105 of the wire rope or cable upon the plug.

Disposed within the tapered chamber in the socket members 12 and 16 above the ring 22 is a pair of rope or cable engaging members or slips 24, each of which is substantially semicircular in cross section, and provided on its inner flat face with a vertically 110

disposed groove 25, the surface of which is formed with vertically disposed ribs 26 that are adapted to grip the surface of the interposed wire rope or cable when the parts are 5 properly assembled. The curved outer faces of the slip members 24 gradually taper toward their upper ends so that said members, when properly associated, form an elongated tapered member that will fit snugly within 10 the tapered chamber in members 12 and 16.

Arranged within the upper end of chamber 17 in the upper member 16 is a packing ring 27 that is engaged by the upper ends of the slip members 24 and which is effective in preventing sand, water, or the like, 15 from passing through the aperture 20 in the upper end of member 16 and entering the tapered chamber within the socket members 12 and 16.

20 When the parts of my improved wire rope socket are properly assembled they occupy the positions illustrated in Fig. 1, and when so arranged the end of the wire rope or cable is very effectively clamped within the socket, 25 and the lower portion thereof may be readily applied to or removed from the threaded extension 11 of the drill shank 10.

To disconnect the wire rope or cable from the socket, upper member 16 is unscrewed 30 from lower member 12 and lifted a suitable distance upon the rope or cable 19, and as a result of blows of a hammer or like tool upon the upper ends of slip members 24, the latter may be driven downwardly through member 35 12 until the rings 22 and 23 and plug 20 are positioned below the lower end of member 12, and when so positioned said rings and plug may be readily separated and disengaged from the spread wires at the end of 40 the rope or cable.

A wire rope socket of my improved construction is comparatively simple, is capable of being readily assembled or taken apart, and is very effective in performing its intended functions. 45

It will be readily understood that minor changes in size, form and construction of the various parts of my improved wire rope socket may be made and substituted for those 50 herein shown and described without departing from the spirit of my invention, the scope of which is set forth in the appended claims.

I claim as my invention:

55 1. A wire rope socket comprising a drill engaging member having a chamber which gradually tapers toward its upper end which chamber is adapted to receive the end portion of a wire rope or cable, a pair of tapered rope clamping members removably positioned within said tapered chamber, and means within the lower portion of the tapered chamber and below said rope clamping members for engaging the terminal portions of the wires of the rope or cable. 60

65

2. A wire rope socket comprising a pair of detachably connected members in which are formed tapered chambers, the upper end of the upper member being provided with an opening adapted to receive a wire rope or 70 cable, co-operating cable gripping members arranged in the upper portion of the tapered chamber formed in the socket members, a plug positioned between the ends of the wires of the engaged cable beneath said gripping members which plug is provided with opposite disposed tapered portions, and rings encircling the tapered portions of said plug and the wires of the cable that are positioned thereupon. 75

3. A wire rope socket comprising a pair of detachably connected members within which are formed connecting tapered chambers, the upper end of the upper member being provided with a cable receiving opening, the 80 lower portion of the lower member being internally threaded to receive the threaded upper end of a drill shank, and means within the tapered chambers of said connecting members for gripping a cable. 85

4. A wire rope socket comprising a pair of detachably connected members within which are formed connecting tapered chambers, the upper end of the upper member being provided with a cable receiving opening, 90 the lower portion of the lower member being internally threaded to receive the threaded upper end of a drill shank, and a cable gripping means arranged within said tapered chamber which gripping means includes a 95 pair of tapered cable engaging members that extend from the upper portion of the lower member of the socket upwardly through the chamber in the upper member of said socket. 100

5. In a wire rope socket, a pair of detach- 105 ably connected members provided with an elongated tapered chamber, and cable gripping means arranged within said tapered chamber and including a pair of co-operating plates having ribbed grooves on their inner faces that are adapted to receive a cable to which the socket is applied. 110

6. In a wire rope socket, a pair of detachably connected members provided with an elongated tapered chamber, cable gripping 115 means arranged within said tapered chamber and including a pair of co-operating plates having ribbed grooves on their inner faces that are adapted to receive a cable to which the socket is applied, a plug arranged between the wires of the cable below said cable engaging plates, and rings encircling 120 said plug and the wires positioned thereupon. 125

7. In a wire rope socket, a pair of detach- 130 ably connected socket members, co-operating cable gripping plates arranged within said socket, a plug adapted to be positioned between the wires of the cable beneath said gripping plates, said plug being provided 135

with a pair of oppositely disposed tapered surfaces over which the wires of the cable are extended, and ring members encircling the tapered portions of said plug and the 5 portions of the wires positioned thereupon.

8. The combination with a wire rope or cable, of a plug seated in the end thereof, rings encircling said plug and the wires of the rope or cable arranged thereupon, a pair 10 of tapered cable gripping plates arranged above said plug and rings, a substantially

cylindrical housing inclosing said gripping plates and said plug and rings, said housing comprising a pair of detachably connected parts, there being a cable opening formed 15 through the upper end of the upper part and the lower portion of the lower part being adapted to receive a drill shank.

In testimony whereof I have signed my name to this specification.

D. W. SNOW.
